(57) **CLAIM**

The ornamental design for a shaker lid, as shown, and described.

DESCRIPTION

FIG. 1 is a perspective view of a shaker lid showing our design, in a use condition;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken line shown in FIG. 1 is for the purpose of illustrating environment and forms no part of the claimed design. The remainder of the broken lines depict portions of the shaker lid that form no part of the claimed design.
